AIR CONDITIONER

Parke D. Snavely, Los Angeles, Calif.

Application April 21, 1936, Serial No. 75,584

4 Claims. (Cl. 62—131)

This invention relates to improvements in air conditioners and particularly to that class having a closed insulated ice bunker in which a refrigerant such as dry ice is sealed and a radiator by which a forced current of air is reduced in temperature. More particularly although not exclusively this invention is of portable type whereby it can be installed for service in any desired location such as in a room or other place where it is desired to reduce the temperature of the atmosphere or otherwise condition air.

The primary object of this invention is the production of an inexpensive device of the class stated which will effectively reduce the temperature of the atmosphere in a room or other place and maintain the same at the desired cold degree and humidity. Among further objects are simplicity of construction and greater effectiveness in use than heretofore.

In the accompanying drawing forming part of this specification, Fig. 1 is a vertical central longitudinal section of my invention, taken on the line 1—1 of Fig. 2, and Fig. 2 is a horizontal section taken on the line 2—2 of Fig. 1.

In the drawing, A is a receptacle of rectangular or other suitable shape. Its enclosing walls are preferably insulated against heat and cold. As shown each of its side walls is laminated, to produce strength and consists of an inner comparatively thick layer of insulating board 11, an outer plate of thin finish material such as hard pressed fiber board 12 and an intermediate layer of wood 13, which layers are cemented or otherwise secured together to form a unit. The bottom wall of the receptacle is composed of a layer of wood 14 and a thick layer of insulating material 15 which also are cemented or otherwise secured together. The top wall of the receptacle is also composed of a layer of insulating material 16, a layer of wood 17 and a layer of finish material 18, all of which are cemented or otherwise secured together. The top wall is preferably removable and can be lifted off of the structure to replenish the refrigerant when desired. A recess 19 in the lower surface of the cover admits the upper edge of the side wall of the receptacle to hold the cover in place. The vertical corners of the receptacle are held by the corner pieces 20 in which the edges of the side walls are secured by cementing or other suitable means.

The upper portion of the chamber in the receptacle is divided by a laminated wall 30 into a remaining ice bunker B, and an air circulating chamber. This dividing wall is composed of an insulating layer 31 and a layer of wood 32 which

are cemented or otherwise secured together as a unit. The bottom of the ice chamber is provided with a radiator D which is spaced above the bottom of the chamber leaving a horizontal air passage C. This radiator D resembles a tray 33 made out of aluminum or other suitable preferably non-oxidizable material and formed with inverted cold radiating conical baffle shells 34, part of the pointed ends of which are longer than others to support the load of the radiator 10 and the refrigerant composed of dry ice or other suitable refrigerating material indicated by E.

The cold radiating baffles 34 are evenly distributed across the air passage whereby a current of air may be forced through the air passage below and between the baffles and reduced in temperature. Ingress and egress openings 35 and 36 are provided in the walls of the receptacle through which a current of air is caused to flow through the air passage C and a deflector 31 adjoining passage 36 diverts the air upwardly therefrom.

Spaced from the dividing wall 30 in the receptacle away from the ice bunker is a vertical partition 40 having an opening 41 in which the fan 42 of an electric blower 38 is confined, causing the fan to force air received through opening 35 down the passage between the bunker and partition 40 and horizontally out through the air circulating passage C and between the baffles 34. Thus a current of air is adapted to be propelled by the blower through the air passage and reduced in temperature by the baffle cones. A vertical deflector 29 between wall 30 and partition 40 serves to prevent churning effect of the air 35 propelled by fan 42. The blower is mounted by a bracket 39 on the wall of the receptacle adjoining the ingress opening 35. The baffles are preferably evenly staggered in one horizontal direction across the tray to increase radiation of the air traversing therebetween and are arranged in straight rows transversely so as to reduce radiation when the tray is shifted into a position with the rows of radiating elements extending longitudinally with the direct flow of air through the air channel. The dimensions of the ice tray are uniform longitudinally and transversely whereby, if desired, the tray may be lifted out of the bunker and reinserted with the baffle cones reversed, that is the tray given a quarter turn horizontally and the baffle cones thus arranged in straight rows parallel with the air flow to reduce the surface contact and thereby impart a cool but higher temperature to the current of air when desired. Thus a readily changeable 55

baffle is provided by which the air may be chilled to either one or the other of two temperatures. The chilled air is substantially dry and free from objectionable moisture. This condition is augmented by a pan 51 which is secured to the lowermost terminal points of the baffle shells 34 by brazing or other suitable means and provided with supports 41 which support the pan spaced above the floor of the receptacle. This pan catches drip but primarily radiates cold imparted by the radiating shells 34 to reduce the collection of condensation and frost. By the use of the baffles which taper down and are hollow, or either, a more effective cold radiating surface is produced and the tendency to collect moisture and frost is reduced to a minimum. The device being light in weight is adapted for use in any convenient location to reduce the atmospheric condition in a room or elsewhere to a lower temperature.

When desired the air conditioning chamber may be provided with an air filter F which is adapted to intercept the current of air traversing the air conditioning chamber and remove objectionable impurities. This filter may consist of frames 46 holding screens such as 45, said frames being removably rabbeted in slots 47, in the walls of the air chamber and shaped around the motor of the blower 38.

To reduce and assist in preventing the collection of condensation and frost from the ice on the cold radiator elements 34 a sheet or plate G, made out of pressed fiber or other suitable poor heat conducting material is placed freely on radiator D in the ice bunker. This plate is provided with openings 50 corresponding with the open ends of the radiator elements.

In accordance with the patent statutes, I have described the principles of operation of my invention, together with the construction thereof which I now consider to represent the best embodiment thereof, but I desire to have it understood that the structure shown is only illustrative and that the invention can be carried out by other means and applied to uses other than those above set forth within the scope of the following claims.

Having described my invention, what I claim as new and desire to secure by Letters Patent is:

- An air conditioner, consisting of a receptacle divided into a bunker and an air conditioning chamber, said bunker being formed by insulating walls and a floor changeable in position horizontally by which a refrigerant is adapted to be sealed therein, said floor having evenly distributed hollow cold radiating baffles depending into said air chamber, said walls of said air chamber having openings at opposite ends of said baffles whereby a current of air may flow through said receptacle in contact with said baffles, and said baffles being disposed in staggered arrangement in one direction horizontally and in parallel rows in transverse direction horizontally, whereby when the floor is shifted across

the current of air flowing through the receptacle the temperature of the air is changed, and a blower in said air chamber for causing air by forced circulation to flow through said receptacle in contact with said baffles to reduce the 5 temperature thereof.

2. An air conditioner, consisting of a receptacle divided into a bunker and an air conditioning chamber with an air passage from said chamber extending below the floor of said bunker, said 10 bunker being formed by thermo insulating walls and a floor by which a refrigerant is adapted to be sealed therein, said floor having hollow inverted conical cold radiating baffles projecting across said air passage by which air from said 15 chamber is reduced in temperature and the walls of said receptacle having openings into said chamber and from said air passage, and means in said chamber for causing air by forced circulation to flow through said receptacle in contact 20 with the outer surfaces of said conical baffles to reduce the temperature of the air.

3. An air conditioner, consisting of a receptacle divided into a bunker, an air conditioning chamber and an air passage from said chamber extending below the floor of said bunker, said 25 bunker being formed by thermo insulating walls and a floor by which a refrigerant is adapted to be sealed therein, said floor having hollow inverted conical cold radiating baffles projecting across 30 said air passage by which air from said chamber is reduced in temperature and the walls of said receptacle having openings into said chamber and from said air passage, means in said chamber for causing air by forced circulation to flow 35 through said receptacle in contact with the outer surfaces of said conical baffles to reduce the temperature of the air and a plate of poor heat conducting material placed upon the floor of the 40 bunker having openings corresponding with the open ends of said conical radiator elements, to reduce condensation and frost from the refrigerant on the radiator elements.

4. An air conditioner, consisting of a receptacle divided into a bunker, an air conditioning 45 chamber and an air passage from said chamber extending below the floor of said bunker, said bunker being formed by thermo insulating walls and a floor by which a refrigerant is adapted to be sealed therein, said floor having hollow inverted conical cold radiating baffles projecting across 50 said air passage by which air from said chamber is reduced in temperature and the walls of said receptacle having openings into said chamber and from said air passage, means in 55 said chamber for causing air by forced circulation to flow through said receptacle in contact with the outer surfaces of said conical baffles to reduce the temperature of the air, and a pan secured to the lower terminals of the conical shells 60 and spaced above the floor of the receptacle to radiate cold, reduce the collection of condensation and catch drip.
